UNITED STATES PATENT OFFICE.

WILLIAM H. SHARP, OF CHICAGO, ILLINOIS, ASSIGNOR TO BAUER & BLACK, OF CHICAGO, ILLINOIS, A CORPORATION OF ILLINOIS.

SURGICAL SWAB.

1,221,231.

Specification of Letters Patent.

Patented Apr. 3, 1917.

Application filed May 3, 1916. Serial No. 95,014.

To all whom it may concern:

Be it known that I, WILLIAM H. SHARP, a citizen of the United States, residing at Chicago, in the county of Cook and State 5 of Illinois, have invented certain new and useful Improvements in Surgical Swabs, of which the following is a specification.

This invention relates to a surgical swab and has for its principal object the provision of a simple and inexpensive means for transporting small quantities of a cleansing, antiseptic or healing liquid in a manner best adapted to render it quickly available and readily applicable when needed.

Other objects and advantages of my invention will be apparent as it is better understood by reference to the following specification when read in connection with the accompanying drawing, illustrating the preferred embodiment thereof, in which—

Figure 1 is a view in perspective of a surgical swab according to my invention;

Fig. 2 is a view in perspective of the liquid container;

Fig. 3 is a view in perspective of the absorbent pad;

Fig. 4 is a view in perspective of the wrapping, and

Fig. 5 is a longitudinal section through 30 the swab as illustrated in Fig. 1.

Referring to the drawing, 1 indicates a suitable friable container, preferably of glass and sealed to normally retain the liquid 2 contained therein. The liquid 2 may be 35 cleansing, antiseptic or healing in character, the swab being especially designed, however, to contain small quantities of iodin and to permit the ready application thereof to wounds. A cover 3 of textile material, preferably gauze bandage, is arranged about the container 1, the purpose being to prevent the escape of the glass or other friable material when the container 1 is broken. A pad 4 of absorbent material, such as absorbent cotton, 40 surrounds the container 1 and a wrapping 5 of textile material, such as gauze bandage, is disposed about the pad 4 and is folded beyond the pad 4 to form a handle 6. The

handle 6 is bound with cords 7 to retain the parts in assembled relation. The portion 50 of the wrapping 5 forming the handle 6 is impregnated with a liquid resistant material, such, for example, as paraffin, to prevent absorption of liquid thereby when the container 1 is broken.

To utilize my invention it is necessary merely to crush the container 1 whereupon the liquid 2 escapes and permeates the pad 4 and the wrapping 5, so that the liquid is readily applied to any desired surface, as 60 for example the application of iodin to a wound. The fingers of the user are, however, protected from contact with the liquid by impregnation of the handle 6 and consequently the swab may be used with great 65 facility and without waste of the contents thereof. When the contents of the container 1 is exhausted the swab is discarded. The cover 3 prevents particles of the container 1 from working through the pad 4 and 70 causing injury during the application of the liquid 2.

My invention is particularly desirable in connection with first aid packages now commonly supplied soldiers and others for applying iodin to wounds since small but sufficient quantities of iodin may be readily carried by individuals in a form which makes it quickly available and readily applicable when needed. It will be apparent, 75 however, that my invention is not necessarily limited to the transportation and application of iodin but may be employed with a great variety of liquids of cleansing, antiseptic or healing character.

It will be further apparent that I have perfected a surgical swab which because of its compactness, simplicity of construction and the ease with which the contents may be released and applied fills a long-felt need 80 in the art.

It will be further understood that various changes may be made in the form, construction and arrangement of the parts without departing from the spirit and scope of the invention, or sacrificing any of

its material advantages, the form hereinbefore described being merely a preferred embodiment thereof.

I claim:

- 5 A surgical swab comprising a friable liquid container, a pad inclosing said container, and a wrapping of textile fabric surrounding said pad and extending beyond the pad and folded upon itself to form an

elongated handle, said handle being impregnated with a liquid resistant material to prevent absorption of the liquid thereby when the container is broken. 10

WILLIAM H. SHARP.
